GARMENT

Morris Staw, New Brunswick, N. J.

Application July 16, 1932. Serial No. 622,878

5 Claims. (Cl. 2—95)

This invention relates to garments, and is particularly directed to improvements in a garment of the general type, disclosed in my co-pending application, hereinafter mentioned, and which 5 may be worn either as a coat or as a shirt, or as a combination coat and shirt.

An object of this invention is to provide in a garment of the character described, a shirt front simulating member comprising a complete collar 10 having a folded over portion, and which may be attached to the coat in such a way that the collar will be retained in neat condition.

A further object of this invention is to provide a garment of the character described, having a 15 shirt front simulating member which may be retained in substantially flat and neat condition by means of a band extending around the back of the wearer.

A still further object of my invention is to provide in a garment of the character described, a 20 modified form of shirt front simulating member having separate folded over collar portions adapted to be exposed when the garment is worn, the construction including means for retaining 25 said portions in folded down position.

Still another object of this invention is to provide a neat, attractive garment of the character described, which shall be relatively economical to manufacture, comprise few and simple 30 parts, which shall be easy to don and doff, comfortable to wear, particularly in warm weather, and which shall be practical and efficient to a high degree in use.

Certain features shown, described and claimed 35 in this application, are shown and described, but not claimed, in my co-pending application, Serial No. 572,759, filed November 3, 1931.

In the accompanying drawing, in which is shown one of the various possible illustrative 40 embodiments of this invention,

Fig. 1 is a perspective view of the garment embodying the invention shown worn on a figure, as a shirt, with parts broken away to show the 45 interior construction;

Fig. 2 is a front view of a modified form of a garment embodying the invention shown on a figure worn as a combination coat and shirt;

Fig. 3 is an enlarged, perspective view of the 50 shirt front simulating member shown in Fig. 1;

Fig. 4 is a cross-sectional view taken on line 4—4 of Fig. 3;

Fig. 5 is a fragmentary, still further enlarged, detail view of a portion of the shirt front simulating member shown in Fig. 3;

Fig. 6 is a front elevational view of the shirt front simulating member shown in Fig. 2;

Fig. 7 is a fragmentary front elevational view of another modified form of shirt front simulating member;

Fig. 8 is a partial, detail view of a portion of the shirt front simulating member shown in Fig. 7; and

Fig. 9 is a cross-sectional view taken on line 9—9 of Fig. 7.

Referring now in detail to the drawing, 10 designates a garment embodying the invention, shown in Fig. 1 for the purpose of illustration, as a garment which may be worn either as a coat or as a shirt, or as a combination coat and 15 shirt. The garment is particularly useful for wear in warm weather and may be made of ordinary shirting material such as cotton, silk, rayon, broadcloth or any other suitable material, and may be manufactured without canvas lining or 20 backing. The garment may be cut in accordance with designs and dimensions for shirts, and as will appear hereinafter, will nevertheless have the appearance of a man's coat or combination 25 coat or jacket and shirt.

The garment 10 shown in Fig. 1 comprises generally a coat portion 11 and a shirt front simulating member 12. The coat portion, as stated above, is preferably made of light shirting material and comprises lapels 14, sleeves 15, breast 20 pockets 16 and side pockets 17. The coat 11 is preferably cut to fit the body somewhat loosely in the manner of a shirt, instead of extremely snugly as is usual with the ordinary man's jacket.

The shirt front simulating member 12, shown 25 in greater detail in Fig. 3 of the drawing, may be made of two sections 19 and 20. The section 19 may be provided with an inner edge 21 having a row of buttons 22. The length of said section 19 may be, as shown in Figs. 1 and 3, such 30 that the bottom edge 23 of said section extends to somewhat above the waist line of the wearer. Said section 19 covers only a portion of the wearer and is provided with an outer side edge 24. Said section 19 is further provided at the 35 neck portion thereof with a folded down collar portion 26 including the point 27. Said portion 26, as will be seen from the illustration in the drawing, extends only to the side of the neck and terminates in a rear edge 28. Adjacent said rear 40 edge thereof, said portion 26 is preferably provided with a snap fastener portion 30 adapted to cooperate with a complementary snap fastener portion 30a sewed to section 19, for retaining 45 said folded portion in folded down position.

The section 20 is constructed substantially similarly to and is symmetrically disposed with respect to the section 19. Said section 20, however, is provided with the usual button holes for receiving the buttons 22. Both the sections 19 and 20 are further provided adjacent the upper ends 34 thereof with button holes 35 adapted to receive buttons 36 sewed to the inside of the coat in proper position for engaging within said button holes.

For retaining the shirt front simulating member 12 in substantially neat, flat condition when worn, said member is provided with a band 37 made of tape or elastic material and attached at 15 the ends 38 thereof to the side edges 24 of the sections 19 and 20. The band 37 is adapted to extend around the back of the wearer as illustrated in Fig. 1. When the garment 10 is worn the tie 40 may be passed around the back of the 20 coat 11 and beneath the rear of the lapel 14. The tie ends may be then passed through openings in the coat disposed beneath the lapels and adjacent the sides of the neck, as illustrated in 25 my co-pending application, Serial No. 572,759, filed November 3rd, 1931, to permit the tie to be passed beneath the folded down collar portions 26.

The coat portion 11, as illustrated in Fig. 2 of the drawing, extends below the waistline and substantially to the hips of the wearer and is of usual 30 jacket or coat length. The lower ends of the garment, however, may be tucked within the trousers so as to give the garment as whole the appearance of a shirt. The bottom of the coat, 35 however, may be worn outside of the trousers so as to give the garment, as a whole, the appearance of a combination shirt and coat. Obviously, the coat portion 11 may be worn without the shirt front simulating member 12, and thus has the appearance and character of a coat or jacket alone, 40 and may be worn in combination with an ordinary shirt of usual construction, or in any other suitable manner.

In Fig. 2 the coat portion 11 is shown as worn 45 in the manner of an ordinary man's jacket. Worn therewith, however, is a shirt front simulating member 12a illustrated in greater detail in Fig. 6 of the drawing. The member 12a is substantially similar to the shirt front simulating 50 member 12 except that the sections 19a and 20a thereof are elongated and are of the length of the ordinary shirt, thus producing shirt tail portions 45 and 46 which may be tucked into the trousers when the coat portion 11 is worn either as shown 55 in Fig. 1 or as shown in Fig. 2.

In Figs. 7, 8 and 9 there is shown a shirt front simulating member 12b which may likewise be worn with the coat 11 shown in either Figs. 1 or 2, and modified as hereinafter described. The 60 member 12b comprises sections 19b and 20b which may be either of the length shown in Fig. 3 or of the length shown in Fig. 6, but which are interconnected at the rear by a portion 47 substantially forming a collar band adapted to extend 65 about the back of the wearer's neck. Extending from and stitched to said portion 47 or the neck portions of the sections 19b and 20b, is a complete folded over collar portion 49. Said portion 49 is provided at the rear thereof and 70 adjacent the lower edge thereof, with a button-hole 50 adapted to receive a button 51 attached to the rear inner side of the coat 11a at the neck portion 52 thereof. The button 51 serves to retain the folded over collar portion 49 in proper 75 position so as to render the collar neat and at-

tractive in appearance, and may constitute the only attachment between the member 12b and the coat. Thus when the coat 11a is worn with a shirt front simulating member 12b, the openings in the coat which permit the ends to pass therethrough, may be omitted since the tie may be passed around the neck portion 47 and beneath the folded over collar portion 49. Furthermore, the buttons 36 on the inside of the coat which are received in the button holes 35 of the shirt front simulating member 12, may likewise be omitted from the coat 11a when used in conjunction with the member 12b. The member 12b may likewise be provided with a band 37 extending around the back of the wearer for retaining the sections 19b and 20b in substantially flat, uncreased condition.

It will be seen that there is provided a device in which the several objects of this invention are achieved, and which is well adapted to meet the conditions of practical use.

As various possible embodiments might be made of the above invention, and as various changes might be made in the embodiments above set forth, it is to be understood that all 100 matter herein set forth or shown in the accompanying drawing is to be interpreted as illustrative and not in a limiting sense.

Having thus described my invention, I claim as new and desire to secure by Letters Patent:— 105

1. A garment comprising a coat made of light shirting material adapted to be worn on the upper portion of the body, split entirely down the front to permit the garment to be doffed in the manner of a coat, said coat being buttoned 110 at the front and having a collar and lapels, and extending below the waist of the wearer, and a shirt front simulating member having portions adapted to be buttoned to each other, said portions being interconnected around the back of 115 the neck and having a folded over collar portion, and means for detachably fastening the rear of the folded over collar portion to the inside of the coat at the rear neck portion of the latter.

2. A garment comprising a coat portion and a 120 shirt front simulating member having portions buttoned at the front, and a neck portion interconnecting said first two portions, and a folded over collar portion, and means for attaching the rear portion of said folded over collar portion to 125 said coat portion adjacent the rear neck portion of the latter.

3. A garment comprising a coat, a shirt front simulating member for said coat, said member having a folded over collar portion, and means 130 for detachably attaching the rear of said folded over collar portion to said coat in folded down position.

4. A garment comprising a coat, a shirt front simulating member detachably attached thereto, 135 and a band attached at the ends thereof to opposite portions of said shirt front simulating member and extending about the back of the wearer, said shirt front simulating member having a complete folded over collar portion, and means for detachably attaching said folded over collar portion to said coat portion.

5. A garment comprising a coat portion and a shirt front simulating member, said member having a front portion, a portion extending around 145 the neck and a folded over collar portion, and means for detachably attaching said folded over collar portion to said coat portion.
